METHOD OF AND APPARATUS FOR EXPLODING ARMOR PIERCING PROJECTILES

Harry J. Nichols, Dayton, Ohio, assignor to the United States of America as represented by the Secretary of the Navy

Application October 25, 1932, Serial No. 639,505

7 Claims. (Cl. 102—75)

1

My present invention relates to new and useful improvements in a method of and apparatus for exploding armor piercing projectiles for substantially increasing their efficiency and rendering certain the delaying of their explosion until after they have passed through the armor.

Explosive projectiles of the armor piercing type heretofore used have proved unsatisfactory for the reason that the great force of their flight-impact upon armor and/or the distortion of the projectile due to such impact as well as to the penetration of armor, especially at a substantial angle, causes such friction due to the consequent changes in position of the contacting particles of compressed explosive as to detonate such explosives, usually when the same is entirely outside of or partially entering the armor and ordinarily without obtaining the substantial effect which such explosion would have produced within the armored area.

In some types of warfare projectiles detonating upon flight-impact are desirable and many such devices have been provided therefor, but in naval warfare such projectiles are ordinarily undesirable and with modern armor they are practically useless.

I have heretofore devised an explosive filler for a projectile which will not be detonated by the flight-impact of its projectile upon armor due to its projectile piercing armor even at a substantial angle. That invention forms the subject-matter of my co-pending application Serial Number 708,106, now Patent No. 1,848,193. This application provides a method and means to make certain the explosion of such filler after passing through the armor.

The basic objects of my present invention are to provide a method of and apparatus for practically and dependably withholding detonation upon minor flight-impacts, dividing the steps of detonation into two of which the first is the initiation of detonation preceding the projectile explosion by a time interval, initiating detonation only upon a major flight-impact, and variably delaying said time interval by and/or proportionately to the various rates of deceleration which the velocity of the projectile in flight may possibly encounter incident to major flight-impacts; all preferably by one and the same production, and production-assembly, of projectiles without the necessity of any subsequent manual adjustment.

My new and improved method relative to armor piercing projectiles containing explosive charges, may be stated to contemplate and include

2

the steps of (1) uniformly constructing and adjusting the same; (2) withholding the initiation of detonation and/or deflagration of the explosive content upon the minor flight-impacts of such projectile; (3) permitting such initiation only upon a major flight-impact of such projectile; (4) variably delaying the initiation of detonation relatively to the different decelerations of similar projectiles incident to piercing armor of different deceleration characteristics, and then accomplishing said initiation; (5) exploding the projectile.

My said method also contemplates that the explosive content which initiates detonation and which ultimately explodes the projectile may be separated from each other and relatively movable and that such relative movement shall be in a direction opposite that of the flight of the projectile.

20 My apparatus contemplates and includes a projectile adapted to pierce armor even at a substantial angle and adapted to contain a major volume of explosive, preferably that disclosed in my said co-pending application; a fuse and a booster charge each independent of and normally non-communicating with the other; means for relatively movably confining the fuse and the charge whereby they may be brought into communication with each other, this relative movement being mainly in a direction substantially different from, or opposite to, that of the flight of the projectile; means for producing the relative movement; means for releasably restraining such movement during minor flight-impacts of the projectile; means for variably delaying the actuation of the released actuating means; means for initiating detonation of the fuse by or at substantially the culmination of the relative movement; and means for variably delaying the deflagration, each of the variable delay means being adapted to delay by, or in substantial synchronism with, the differences in the deceleration forces incident to similar projectiles piercing armor of substantially different deceleration characteristics; means for locking each of said initiating means and said restraining means respectively in an unarmed and in a restraining position as well as respectively in an armed and in a released position.

40 These and other objects and exemplifications of my invention will be more apparent from the following detailed description and the accompanying drawings illustrating one embodiment of my invention in an improved apparatus, of the 45 many different forms and characters of appara-

55

tus each of which may be employed in the advantageous practice of my improved method, and each of which like characters of reference denote the same part.

In the drawings,

Figure 1 represents a central longitudinal sectional view of a fuse unit for an armor piercing projectile constructed and functioning in accordance with my invention, and illustrating the parts in their uniformly constructed and adjusted positions which are maintained under all circumstances until after the initiation of the flight of the projectile;

Figure 2 is a view substantially similar to Figure 1 but showing the fuse-carrier unit not in section and illustrating the positions of the parts released and assumed in the flight of the projectile;

Figure 3 is a view of the forward portion of and substantially similar to Figure 1, but showing the relative position of the parts released and assumed upon a major impact of the projectile;

Figure 4 is substantially a composite of Figures 1 and 2, but showing the further different relative position of the parts upon the initiation of detonation of the fuse;

Figure 5 is an enlarged central vertical sectional view of the cap 18;

Figure 6 illustrates the cap shown in Figure 5 as viewed from the end that faces the fuse;

Figure 7 is an enlarged sectional view on line 7-7 of Figure 1;

Figure 8 is an enlarged sectional view on line 8-8 of Figure 2;

Figure 9 is an enlarged central vertical sectional view of the fuse carrying unit showing tube 102 positioned by a major impact;

Figure 10 is an enlarged central vertical sectional view of the firing pin shown located in its armed position;

Figure 11 is a front elevation view of a member of the fuse unit receiving the flame from the detonating cap.

The device as a unit is preferably formed of a central cylindrical element 18 having a plurality of preferably outwardly flared openings 19 extending radially through the wall element 18 and equally disposed about the periphery thereof. At the center of element 18 is a cylindrical bearing opening 20 extending longitudinally of element 18. At the forward end of element 18, opening 20 communicates with an enlarged cylindrical opening 21 extending to the forward end of element 18. Substantially coextensively with opening 21 the element 18 is reduced in diameter and is provided with external screw threads 22 terminating in a preferably square shoulder 23. The rear of opening 20 communicates with a central longitudinal opening 24 in element 18 terminating preferably in an enlarged central longitudinal opening 25 whose rearward internal terminal is provided with screw threads 26 of desired extent. Intermediate openings 20 and 25 is a shoulder 27 which is preferably formed of a substantial taper.

The openings 19 terminate in cylindrical openings 28 extending between and connecting bearing opening 20 and flaring openings 19 (Figure 7). Fitted within each opening 28 is a cup 29 preferably of thin copper whose closed end is adjacent the periphery of opening 20 but does not extend thereto. The edges of the cup 29 are flared outwardly to conform to and fit against the adjacent walls of their respective openings 19.

The fuse is formed, in the instance shown, of a

cylindrical member 30 adapted to slide in bearing opening 20 of unit 18 that is provided with a shoulder 31 substantially conforming to shoulder 27 of unit 18. Shoulder 31 terminates in an integral enlarged cylindrical portion 32 having an enlarged head 33 upon its rear portion. A relatively heavy coiled spring 34 is loosely mounted upon portion 32 and is adapted to exert its thrust between base 33 of the fuse and the shoulder 31 at the forward end of opening 24.

At a plurality of points about base 33 are secured radial pins 36, functioning as keys and adapted to slide each in their respective keyways 37 formed in the wall of opening 24. An annular groove 38 is formed at the forward end of key-ways 37 and of greater depth than the keyways for convenience in machining. The cooperating pins 36 and key-ways 37 hold the fuse from rotary movement but permit movement of the fuse in casing 18 in a longitudinal direction. Extending peripherally about bearing 30 near its forward end is a preferably circular groove 39, whose rearward edge is normally adapted to be in substantial alignment with the shoulder 40 at the junction of openings 20 and 21. A plurality of balls 41 are mounted in said groove 39 and are retained therein by a ball race consisting, in the instance shown, of a portion of the interior surface of a longitudinally disposed cup-shaped cavity 43, formed in the rear end of retaining member 44 disposed in opening 21.

In base 33 of the fuse is a peripheral groove 45 (Figure 2) having mounted therein a plurality of segments 46 of a ring as shown in Figure 8. The segments 46 are adapted to fit loosely in groove 45 so that the centrifugal force of the projectile revolving about its longitudinal axis in its flight, due to the rifles of the gun barrel from which it was projected, will cause segments 46 to bear outwardly against the wall of opening 24, while the fuse is being moved rearwardly relatively to element 18. In such position the fuse unit is locked by segments 46 bearing against the side of groove 45 and against the forward shoulder 47 between openings 24 and 25, as hereinafter explained. Formed in the outer periphery of retainer 44 is a peripheral groove 48 mounting a plurality of segments 49, respectively similar to 45 and 46 heretofore described. Segments 49 are adapted, by the centrifugal force of the flight of the projectile, to bear outwardly against the wall of opening 21, and when retainer 44 is moved forwardly, as will hereinafter be described, segments 49 will likewise engage the wall of enlarged opening 50, formed at the mouth of opening 21, and lock retainer 44 in position by the engagement of segments 49 against the shoulder 51 at the junction of openings 21 and 50.

Threads 22 engage corresponding threads in the mouth of a cup 52 that has a central longitudinal opening 53 therein, preferably a continuation of opening 50, and a centrally disposed longitudinally extending opening 54 forwardly of and of lesser diameter than opening 53. The forward end of retainer 44 is formed of a cylindrical integral pin 55 that is slidable into opening 54. Between the pin 55 and retaining portion 44 is a shoulder 56 adapted to engage shoulder 57 between openings 53 and 54 as hereinafter described. On the forward end of pin 55 is a portion 58 of reduced diameter adapted to be normally engaged by the inner ends of a plurality of pins 59, each slidably mounted in a hole extending radially from the outer surface of cup 52 into opening 54. Each of pins 59 is provided

with a central longitudinal opening 60 that extends from its outer end and contains a coil spring 61 bearing against the bottom of opening 60 and against a member 62 adapted to close the outer end of opening 60.

In the joint between cup 52 and element 18 is a pin 63 for preventing the turning of cup 52 on threads 22.

Into each of the openings 19 is pressed a substantial amount of explosive 66 which is herein termed "booster-charge," and which, with explosive content of the projectile, is preferably formed of the explosive composition forming the subject matter of my co-pending application Serial No. 708,106. A cupped shell 64 of relatively thin metal encloses cup 52 and extends over the forward portion of fuse element 18 to a point rearwardly of the booster charges 66. At its edge and at a plurality of points in its length shell 64 is spun or swaged into peripheral depressions 65 formed in said parts 18 and 52 for the purpose of retaining booster charges 66 in their respective openings 19 as well as further preventing the separation of parts 18 and 52 and retaining heads 62 against the thrust of springs 61.

Into the threaded opening 26 is screwed the threaded forwardly projecting end 67 of cylindrical body 68 provided with externally threaded portion 17 and rear terminal flange 70.

Referring to Figure 10, in end 67 is formed a central longitudinal opening 71, terminating in a conical bottom 72 from which is substantially centrally rearwardly extended an opening 73 adapted to receive a plurality of balls 74, as shown in Figure 1. In opening 71 is mounted to slide freely the enlarged head 75 of a firing pin 76, having a conical portion 77 conforming to the shape of bottom 72. Intermediate pin 76 and its head 75 is a cylindrical portion 78. Enlarged threaded mouth 79 of opening 71 receives a threaded plug 80 provided with a central aperture therethrough in which pin 76 is slidable, and having pin-holes 81 in its forward face adapted to receive the prongs of a spanner wrench for fitting and removing said plug 80.

Extending radially from the outer periphery of end 67 are a plurality of openings 82 in each of which is mounted a relatively thin thimble 83 within which is slidably mounted a pin 84 having a centrally disposed outer cavity to receive coil spring 85, to exert pressure between pin 84 and a central positioning projection formed in the crown of thimble 83. The inner end 87 of each pin 84 is preferably of a reduced diameter and slidably extends through an opening in the inner end-wall of its thimble 83.

The internal construction of the fuse will now be described with reference to Figures 1, 3, 4, but particularly to enlarged view Figure 9. This unit has a central longitudinal opening 90, provided with an enlarged mouth 91, in portion 30 and extending substantially therethrough. From the bottom or rearward end of opening 90 extends an opening 92, of smaller diameter than opening 90. Opening 92 is joined at its rearward terminal with an enlarged central, longitudinally disposed opening 93 having an enlarged threaded mouth 94. A round collar 100, having gasket ring 101 seated upon its forward end, is mounted in the bottom of opening 93 with gasket 101 firmly pressed against the shoulder between communicating openings 92 and 93. Extending longitudinally through the center of collar 100 is a tube 102 having a tapering forward portion 103 fitting into a corresponding tapering hole through col-

lar 100. In the initial assembly, tube 102 is inserted merely to a nominal extent into the collar (see Figure 1) and is capable of being forced to different depths into or through said collar 100 (see Figure 9) as hereinafter explained. The longitudinal opening through tube 102 is open at its forward end and is closed at its rear end. Near the rearward end of tube 102 are formed a plurality of radial openings 104 through the wall of tube 102. In the rearward end of collar 100 is formed an enlarged centrally disposed longitudinal cavity adapted to receive a relatively short length of tubular compressed powder or other explosive 105 which extends over the rear end of tube 102 and over the openings 104 through the walls of tube 102. Mounted in opening 93 and against the rear surface of collar 100 is a sleeve 110, closed at its forward end and having in the closure a centrally disposed longitudinal opening 106 adapted to slidably receive, as shown in Figures 1 and 13, the rear end portion of tube 102 which projects rearwardly of powder-tube 105. Surrounding opening 106 are a plurality of holes 107 extending longitudinally through the forward wall of said sleeve 110 and into a chamber 111 centrally and longitudinally disposed in the rear end of sleeve 110. In the forward face of collar 110 and surrounding opening 106 is an annular groove 112. Against the rear end of sleeve 110 is mounted a disk 115 having centrally disposed longitudinal opening 116 therethrough. Screwed to the mouth 94 of opening 93 is a plug 117 provided with a centrally disposed longitudinally extending cavity adapted to receive the detonating cap 118 and the central opening 119 therethrough for the passage of firing pin 76 when the firing pin is thrust through opening 119 to fire cap 118.

In the opening 92 is placed an explosive preferably in the form of granulated powder. Opening 90 receives an explosive charge which may consist of compressed powder or other explosive contained in a relatively soft copper shell 120 whose forward end is open and is retained in the shell 120 by a wad 121, which may be of paper or very thin copper, with the mouth of shell 120 crimped over the edges of wad 121. Extending radially from the outer surface of member 30 and adjacent the groove 39, in which are balls 41, are a plurality of radial openings terminating against the shell 120, each of which contains a compressed powder or other explosive pellet 122. Against the end of shell 120 is mounted a detonator seat wad 123, preferably of soft material and held in position by steel or other metallic wads 124 held in place by the mouth of opening 91 the latter being spun or swaged thereover.

The detonating cap 118 will now be described, reference being had more particularly to Figures 5 and 6. The detonating pellet 130 is mounted in the bottom of a thin metallic cup 131, swaged against a portion of the outer surface of a metallic disk 132 having a centrally disposed projecting anvil surface 133 adapted to contact with the top surface of detonating pellet 130. Surrounding anvil portion 133 is one or more preferably inflammable washers 134 extending between disk 132 and detonating pellet 130 and protecting the pellet, before assembly, from exposure to the elements through a plurality of openings 135 extending through said disk 132.

Before detailing the operation of the parts and units in their various positions, it should be un-

derstood that when firing pin 76 drives a portion of the bottom of cup 131 against the anvil 133 of disk 132 the pellet 130 will be detonated, causing the heated gases to heat and force or burn their way through wad or wads 134 and 5 openings 135 through disk 132, thence through central openings 116 in disk 101 to chamber 111 and thence through holes 107 to annular groove 112 where the rearward edge of powder tube 105 is deflagrated. This deflagration of tube 105 10 progresses at a definite rate and its generated gases accumulate in chamber 111, openings 116 and 119 which are of sufficient volume to permit deflagration of tube 105. When the deflagration of tube 105 has reached the depth to which openings 104 of tube 102 may be within the deflagrating tube 105, the inflammable gases therefrom are forced through openings 104 into the hollow of tube 102 to the powder granules in opening 92, whose deflagration is transmitted through wad 20 121 to and detonates the content of shell 120 which detonates the pellets 122.

If the detonation be initiated spontaneously, or otherwise than intended by the design and construction of this method and apparatus, the pellets 122 will be in the position shown in Figure 1 which will be out of communication with each of the booster charges 66 and the projectile will consequently not be exploded, but the gases from the above stated detonation will be contained in the cavities specified and those forward of the fuse bearing unit which are ample to care for the same without tendency to disrupt members 18 and 52 or otherwise detonate the explosive content of the projectile. 30

However, if in the course of the aforesaid detonation pellets 122 substantially register with caps 28, then, and then only, will the booster charges 66 and the explosive content be detonated by the exciting of the caps 28 or the application 40 of the force and/or intense heat of the detonation being transmitted to and through the caps 28 to the booster charge 66 and thence to the explosive content of the projectile.

The tube 105 is preferably formed of powder, or the like, pressed into a tubular mass which burns more slowly than loose powder. 45

The hollow of the tube 92 is preferably filled with granular powder, or the like, as shown in Figures 1 and 3, some of which is scattered into the mouth of the tapering hole through collar 106 and into the bore of tube 102 by the firing of the projectile. This shakes and loosens up said content of tube 92 which may have been confined therin for a substantial period and which may have tended to amalgamate or cake. 50

What is called "creep" will, during the flight of the projectile, cause the content of tube 92 to pack against the wad 121 of casing 120. A minor impact of the projectile will further pack and solidify the content of tube 92 against wad 121. A major impact of the projectile will still further pack and solidify said content of tube 92 against said wad 121, and such impact drives the end of tube 102 against the end of the explosive in tube 92 and penetration. In practice it has been found practicable with my invention by proper calculation or experimentation to determine the force of spring 34 and the weights of the fuse carrying member movable by said spring and the weights of tube 102 and retainer 44, and to proportion the same such that the bursting of the projectile is attained at approximately the same distance behind the several 55

thicknesses of armor ordinarily employed in the construction of ships of war.

The disk 132 is provided with a recess 132a, in its forward face communicating with openings 135 (Figures 5 and 6) and 116 (Figure 9) to form a passageway for the burning gases formed by the detonation disk 133. Intermediate metallic wad 115 and cap 118 is provided a deflagrating wad 107a (Figure 9) having a central aperture therethrough in alignment with opening 116.

Openings 117a (Figure 9) in the rear face of plug 117 accommodate the prongs of a spanner wrench for convenient placing and possible removal of plug 117.

In the shouldered joint between body 68 and member 18 is provided a pin 68a to prevent the unscrewing of the threaded connection between members 68 and 18.

In the rear surface of body 68 is formed a central longitudinal opening 140 (Figure 1) having an enlarged rear threaded mouth 141 adapted to receive at will either a suitable screw plug to close the opening or a tracer-fuse unit 142 having threaded rear portion adapted to be engaged by threads 141 to retain the same in position. Unit 142 is provided with a central longitudinal cavity extending from its rear face for the reception of a deflagrating medium 143 in its forward end, booster charge 144 in its rearward portion, sealed by wad 145 preferably of thin copper or deflagrating material held in position by metallic wad 146 having central opening 147 therethrough and crimped or swaged in the mouth of opening 140. When the projectile is fired from the gun the hot gases pass through opening 147 and cause the deflagration of booster charge 144 and tracer-fuse 143, affording a flame of any desired color issuing through opening 147 to form a suitably colored flaming path by which the actual trajectory of the projectile may be readily observed.

Upon the shell being fired, the force of the explosion suddenly imparts a high velocity to the projectile which causes parts 75 and 44 to be pressed more firmly against their respective seats 72 and 40, and which forces would tend to move the fuse rearwardly but for the balls 41 preventing such movement. In the flight of projectile, the friction of the air or other medium traversed by the projectile tends slightly to decelerate the velocity of the projectile, while the rotary motion of the projectile due to the rifling of the gun barrel, imparts rotation to the projectile about its longitudinal axis. The deceleration of the projectile is not imparted to the firing pin 76 and its integral parts, with the result that they will thereby be moved forwardly from the unarmed position shown in Figure 1 to the armed position shown in Figure 2, due to the centrifugal force of the projectile overcoming the power of and compressing springs 35 and withdrawing the inner ends 87 of pins 84 from interference with such movement of pin 76 and its head 75. The same force which causes firing pin 76 to move forwardly also causes balls 74 to be moved into and be retained in the angular space between head 77 of pin 76 and its seat 72 in body 68. This locks firing pin 76 in its armed position throughout the remainder of the flight of the projectile.

The centrifugal force of the projectile in flight also overcomes the force of springs 54 and moves pins 59 radially outwardly and free from shoulder 58 of retainer 44, as shown in Figure 2, so that

retainer 44 may be moved forwardly by an appropriate force.

If during its flight, the projectile should effect a minor flight impact, which herein contemplates an impact with water in a naval engagement for instance, or with a relatively frail object upon land, the flight velocity of projectile 10 will thereby be decelerated but the force of such deceleration will be insufficient to change the position of the parts substantially from that shown in Figure 2, which coincides with that illustrated in Figure 1 in all substantial respects except as to pins 76, 59 and 81 as well as of balls 74.

When the projectile makes a major flight-impact, which is herein contemplated as being an impact with armor, the projectile is decelerated thereby at a rate substantially different from that of its possible deceleration incident to a minor flight-impact.

The deceleration force incident to a minor flight-impact is, by the design and construction of the parts, insufficient to release the fuse, but the greater deceleration force incident to a major flight-impact is the only agency which can release the fuse from its secured position illustrated in Figures 1 and 2.

In the position shown in Figures 1 and 2 the relatively heavy spring 34 is maintained under substantial compression by the balls 41 occupying groove 39 about the forward end of the fuse-carrying unit and by those balls in that position bearing against shoulder 40 and being retained in such position by retainer 44, against whose surface 42 the balls 41 exert substantial outward pressure in holding the fuse against rearward movement by the force of spring 34. When the projectile attains a major flight-impact the deceleration force thereof overcomes the restrained force of spring 34 and causes the fuse to be moved forwardly until shoulders 27 and 31 are in contact. This forward movement of the fuse frees the contact between balls 41 and shoulder 40 which frees balls 41 from outward pressure against the surface 42 of retainer 44, due in effect to the normal wedge-like action of curved groove 39 tending to move the balls 41 radially outwardly against shoulder 40 by the normal force of spring 34 exerted upon balls 41 through groove 39. Normally it is the force of spring 34 which causes the outward pressure of balls 41 against the surface 42 of retainer 44. Consequently when the deceleration force incident to a major flight-impact overcomes the force of spring 34 the outward pressure of balls 41 against surface 42 of retainer 44 practically ceases. Consequently there need be no forward motion of the fuse in order to free surface 42 of retainer 44 from the outward pressure of balls 41 due to the wedge-like action of groove 39 upon balls 41, since such wedge-like action is caused by the force of spring 34 tending to move the fuse-carrying unit rearwardly. The freeing of balls 41 from contact with shoulder 40 relieves surface 42 of retainer 44 from any action thereon by balls 41 due to compressed spring 34, whereupon relatively light deceleration force is sufficient, during the period that shoulders 27 and 31 remain in contact, or during the period that the deceleration force overcomes the action of spring 34, to move retainer 44 forward to the position shown in Figure 3 wherein segments 49 are adapted to lock retainer 44 against shoulder 51. In this forward position of retainer 44 balls 41 are free to roll from groove 39 into cavity 43, thereby leaving the member 30 free to be moved

backwardly through opening 20 by the spring 34.

The deceleration force incident to a major flight-impact of a projectile with heavy armor is substantially greater and is exerted throughout a substantially longer period of time than such deceleration force incident to a major flight-impact with lighter armor. This difference in deceleration force varies the period, with armors of different resistances, that such deceleration force overcomes the normal force of restrained spring 34 as well as correspondingly varies the period of time that shoulders 27 and 31 remain in contact; and it is only when such deceleration force ceases to overcome the force of spring 34 that the fuse-carrying unit may be moved rearwardly with its pin 36 sliding in key-ways 37 until detonating cap 118 is brought into contact with firing pin 76 by the released force of spring 34, which initiates the detonation and deflagration of the fuse, as hereinbefore explained, which position is shown in Figure 4, with the centrifugal force of the projectile causing segments 46 to lock against shoulder 47, Figure 2, and maintain the fuse-carrying unit in that position, wherein for the first time since the manufacture and assembly of the projectile the outlets 122 of the fuse unit are brought into communication with caps 28 of booster charges 66 so that upon the completion of the detonation the booster charges 66 as well as the explosive content of the projectile may be detonated.

It will thus be apparent that the initiation of detonation of the fuse is variably delayed according to the resistance characteristics of the armor which the projectile penetrates.

Additional variable delay is accomplished in the instance shown in the drawings, by the deceleration force incident to a major flight-impact forcing the tapering forward end of tube 102 to different depths into and/or through the opening in bushing 100. Tube 102 being thus driven forward by, and relative to, the force incident to a major flight-impact of the projectile, such forward movement will be less when such major flight-impact is with armor of lesser resistance and more where such major flight-impact is with armor of greater resistance. The firing pin 76 contacting with detonating cap 118 initiates the deflagration of the rear edge of the deflagrating tube 105 which continues for a period of time variable to the extent to which tube 102 may be driven forwardly into its bushing 100, and the radial openings 104 through the walls of tube 102 are thus forced to correspondingly variable distances forwardly of the rear edge of deflagrating tube 105. This varies the period in which tube 105 may deflagrate before the deflagration is communicated through openings 104 to tube 102 and thence to the elements 92, 121 and 122 of the fuse and thence to the booster charges 66 and the explosive content of the shell.

The spring 34 is designedly of such force when held under compression by the fuse unit that such force will be overcome only by the deceleration force incident to a major flight-impact.

The tapering forward end of tube 102, with its coacting tapered opening in the forward end of bushing 100, are designedly of such relative proportions that the deceleration force incident to a major impact will drive tube 102 into said collar substantially proportionate to the magnitude of such deceleration force, which varies with armors of different resistances, and thus varies the deflagrating period required for tube 105 to burn down to openings 104 of tube 102.

The initiation of detonation of cap 118 is variably delayed due to the varying period that the deceleration force of the projectile in piercing armors of different resistance characteristics, which, with the variable period required for tube 105 to burn down to openings 104 of tube 102, is designed not to produce the explosion of the projectile until it has attained a definite distance behind the armor it has pierced. This distance may be varied for armors affording substantially the same deceleration to like projectiles by varying the power of spring 34 and/or varying the taper of tube 102 or the weight of tube 102, or otherwise.

It will be apparent that the projectiles are all made and uniformly assembled, and that the variable delay in initiating detonation after the initial occurrence of a major flight-impact, as well as the variable delay between such initiation and the explosion of the projectiles are each occasioned not by any variation in the manual adjustment of any of the parts but solely by differences in the deceleration forces incident to the different resistance characteristics of the armor encountered and which may be unknown to those initiating the flight of the projectile or projectiles.

It will be further apparent herefrom and from the instance shown in the exemplifying apparatus that it is the force of the spring 34 which distinguishes between minor and major flight-impacts of the projectile in the sense that minor such impacts do not, while major such impacts do, result in the initiation of detonation.

Another valuable feature of my invention is that the force, for instance, of spring 34 may be designed for different mediums with which projectiles may minor flight-impact where such mediums afford substantially less resistance than armor. Projectiles designed to pierce heavy armor are usually different in caliber from those planned for piercing lighter armor and may be of different forces of springs 34 whereby the former in minor impact may encounter deceleration exceeding that of light armor and yet not explode until and unless they achieve a major impact. However, the fuse units and projectiles may be of uniform sizes as to their threaded portions, and as to the exterior size of units so that by the substitution of a lighter unit a projectile for heavy armor may pierce relatively light armor and explode its greater explosive content the requisite distance behind or within the same.

The cups 29 in the inner mouths of openings 28 prevent any tendency of booster explosive charges 65 to corrode or otherwise impair the sliding bearing of fuse unit portion 30 in body 18.

The fuse, and the booster or other explosive content being maintained out of communication with each other until an explosion of the projectile is designed to occur, substantially contributes to the safety of the projectile under all other conditions.

My method provides certainty in the region where the projectile is explodable regardless of its minor impacts; that its exemplifying apparatus affords standard construction and assembly which is safe in handling and under all circumstances (except extreme heat) until after a major impact; and that the requisite adjustments of the parts are occasioned by the characteristics of the major impact to variably determine the place of explosion of the projectile.

I have herein described my method together with its exemplifying apparatus which I now consider to represent the best embodiment of my

invention to obtain the most advantageous results, but I desire to have it understood and appreciated that the apparatus shown is only illustrative and that my method may be advantageously practiced by other means which may be readily selected and adapted by those skilled in the art after becoming familiar with my method; and that the method and apparatus features of my invention in their basic contemplation are entitled to a broad range of equivalents. Furthermore, while it is designed in the obtainance of the most satisfactory results to employ the various steps, features and elements of my method and apparatus in the combination and relations described, many of these may be separately used, altered or omitted without interfering with the more general result or results indicated, and that my invention contemplates and extends thereto.

I claim:

1. The method of controlling the explosion of a projectile having an explosive content and a fuse, comprising the step of compacting the deflagrating material of the fuse proportionately to the deceleration force encountered by the projectile in its flight.

2. In a projectile fuse unit, an axially bored fuse body member having a reduced portion at its forward end and an annular groove in said portion, there being a plurality of apertures through said reduced portion adjacent said groove, the bore therein being large in the larger portion and smaller in said reduced portion and constricted therebetween, means closing the forward end of said bore, deflagrating pellets in said apertures, a thin metal shell in the bore in said reduced portion, compacted deflagrating material in said shell, relatively loose deflagrating material in said constricted portion, a bushing in the

forward end of the large part of said bore, a member slidably mounted in said bushing and having a tapered forward portion movable into the constricted portion of said bore, there being in said member a bore extending from the forward end thereof through the greater part of the length of said member and laterally extending apertures outwardly therefrom, deflagrating material in said bushing around said apertures, a sleeve having a closed end disposed against said bushing, there being an annular groove in the outer face of said end adjacent the deflagrating material in said sleeve and apertured washer disposed against the rear end of said sleeve, a primer disposed against said washer, a plurality of arcuate segment members mounted disposed in an external groove adjacent the rear end of said body member; a substantially hollow enclosing member in which said body member is mounted, the opening therein having a constricted portion in which the reduced end of said body member is slidably, there being outwardly flaring apertures opening into said constricted portion, ignition transmitting closures in the inner ends of said apertures, booster charges in said apertures, a spring under compression disposed in the enclosing member around said body member, to exert backwardly directed pressure against said body, a shoulder in said enclosing member engageable by said arcuate segments when said body member is moved rearwardly to the firing position, a base member engaged with and in part extending into said enclosing member, a firing pin slidably mounted in said base and movable forwardly to a position such that

75 said primer may be struck thereby, centrifugally

releasable means to hold said firing pin in a retracted position, balls disposed to be movable to lock said pin in the projected position, a keeper slidably mounted in the forward end of said enclosing member, there being a recess in the rear end of said enclosing member, there being a recess in the rear end of said keeper, arcuate segments mounted in an external groove in said keeper, a shoulder in said enclosing member engageable by said segments in said keeper when said keeper is moved forwardly, balls normally retained by said keeper in the groove in the forward end of said fuse body but movable into the said recess in said keeper when said keeper is moved forwardly, a cup member connected to the forward end of said enclosing member and into which the forward end of said keeper is movable, centrifugally releasable means to hold said keeper in the ball retaining position, and a thin metal shell enclosing said cup member and said enclosing member to a line rearwardly of said booster charges.

3. In a projectile fuse unit, enclosing means, booster charges disposed therein, a fuse including a primer slidably mounted in said means, said fuse having an annular groove adjacent its forward end, balls normally disposed in said groove, a keeper disposed to retain said balls in said groove, centrifugally releasable means to lock said keeper in the ball retaining position, means to lock said keeper out of said ball retaining position, a firing pin, centrifugally releasable means to hold said pin normally in a retracted position, means to hold said pin in a projected position, and means to move said primer back into detonating contact with said pin upon cessation of a decelerating force after said keeper has been moved to release said balls and said pin has been moved into the projected position, the said movement of the fuse being effective to move said fuse into position to deflagrate said booster charges.

4. In a projectile fuse unit, enclosing means, a fuse including a primer slidably mounted therein, means to hold said fuse normally in an operative position, said holding means being adapted to be released by centrifugal force and for impact of the projectile, means to move said fuse when so released, a firing pin having a conical head and a shoulder, said head being movable in a recess having a conical end wall, balls normally disposed in a recess that communicates with the said conical end of the aforesaid recess and adapted to move out into the aforesaid recess when said pin is projected, and centrifugally releasable means engaging the shoulder on said pin to hold said pin in a retracted position, said pin being movable into a projected position by the deceleration of the projectile to detonate said primer when said fuse is moved by the said fuse moving means, said fuse being in position to deflagrate a charge outside said means when in the primer detonating position.

5. In a projectile fuse unit, enclosing means, booster charges carried thereby, a fuse including a primer slidably mounted therein normally out of position to deflagrate said charges, means to lock said fuse in the said position releasable by centrifugal force and deceleration of the projectile, means to move said fuse into position to deflagrate said charges after said fuse is so released, means to detonate said primer when said fuse is so moved, compacted deflagratable material in the train of said fuse, relatively loose compactable deflagratable material in said train, a second body of compacted deflagratable material disposed to be deflagrated by said primer, and a member in said fuse variably movable proportionately to the deceleration of the projectile to compact said loose material in proportion to its movement and establish variable communication between said loose material and said second body of compacted material proportionately to the movement of said member.

6. The method of controlling the explosion of a projectile having an explosive content and fuse, comprising the steps of providing relatively loose deflagrating material in the fuse and compacting said material proportionately to the deceleration force acting on the projectile in its flight.

7. In a projectile fuse unit, enclosing means, booster charges disposed therein, a fuse including a primer slidably mounted in said means, said fuse having an annular groove adjacent its forward end, balls normally disposed in said groove, a keeper disposed to retain said balls in said groove, centrifugally releasable means to lock said keeper in the ball retaining position, means to lock said keeper out of said ball retaining position, a firing pin operative to detonate said primer, and means to move said fuse to make primer detonating contact with said pin upon cessation of a decelerating force after said keeper has been moved to release said balls from said groove.

HARRY J. NICHOLS.
